UNITED STATES PATENT OFFICE.

EUGÈNE SCHNEIDER, OF LE CREUZOT, FRANCE.

EXPLOSIVE PROJECTILE.

1,257,126.

Specification of Letters Patent. Patented Feb. 19, 1918.

Application filed December 24, 1917. Serial No. 208,713.

To all whom it may concern:

Be it known that I, EUGÈNE SCHNEIDER, a citizen of the French Republic, residing at Le Creuzot, France, have invented a new and useful Improvement in Explosive Projectiles, which is fully set forth in the following specification.

This invention has for its object to provide an improved explosive projectile of known type for mortars and the like guns, comprising a bomb having a larger caliber than the bore of the gun, and therefore remaining outside the bore of the gun during the firing, and having a guiding stem or rod which is inserted into the bore of the gun and which at the instant of issuing from the gun muzzle, engages by means of a tail-piece, a sleeve having steadyng vanes which has up to that instant been kept up against the muzzle of the gun by a relatively weak cord or other connection.

This improved explosive projectile which I prefer to term a "torpedo shell" has the following characteristic features:

1. It is constructed in such a manner that it can be fired from rifled mortars (which can also be employed for firing ordinary shells having a caliber corresponding to that of the mortar), so that the improved torpedo shell has the advantage that it allows of the use of rifled mortars which have a greater precision than smooth-bore mortars.

With this object the torpedo shell comprises a driving base piece having the same caliber as the mortar, upon which said base piece (which is fitted with the usual gas check ring) the explosion of the propelling charge acts and thus propels the entire projectile.

2. The driving base piece fitted with a gas check ring, is preferably constructed to act as a shock absorber, and for this purpose it contains a body of plastic material which on being crushed by the explosion is forced into the driving base piece, and also dovetails itself, as it were, into the end of the guiding stem of the torpedo shell. Owing to the rigid connection thereby made

at the instant of firing between the driving base piece and the torpedo shell proper by the automatic action of the shock absorber, the torpedo shell thereby receives and retains the same rotational motion as the driving base piece.

3. A further plastic shock absorber is pro-

vided on the guiding stem of the torpedo shell in front of the driving bolster for the vaned sleeve. This further plastic shock absorber is intended to prevent the breakage of the vanes by the impact of the driving bolster.

The vaned sleeve and the driving bolster for the guiding sleeve are preferably shaped to fit tightly one into the other, and to crush the said further plastic shock absorber between them.

This arrangement assures a complete and rigid connection between the torpedo shell, the driving base piece and the steadyng vaned sleeve at the instant of the complete ejection of the projectile.

A practical example of this invention is illustrated in the accompanying drawings in which:

Figure 1 is a longitudinal section partly in side elevation of the complete improved torpedo shell shown in position for firing from a mortar; the latter being partly shown in longitudinal section.

Fig. 2 is a cross section on the line X—X of Fig. 1; and

Fig. 3 is a view, drawn to a larger scale, of the inner end of the driving base piece, fitted with a gas check ring.

As shown, A is the mortar barrel formed with rifling (not shown) whereby it is rendered capable of being used for firing the improved torpedo shells or ordinary shells at will; the said ordinary shells (high-explosive shells or shrapnel) being charged in the usual way, at the breech of the mortar.

The improved torpedo shell comprises in the usual manner a bomb B fitted with its fuse and having soldered or otherwise fixed to its rear end a neck b for the reception of the guiding stem C which is held in place for instance by means of pins c. The readily removable connection between the bomb and its guiding stem by simply slipping on and fixing by means of pins, has the advantage of allowing the improved projectile to be taken to pieces for transport.

The guiding stem may be tubular, in which case it is closed at both ends by means of plugs c¹, c². D is a sleeve provided with a suitable number of vanes D¹ by means of which it is engaged on to the muzzle of the mortar. One of these vanes is formed with a notch d¹ to receive the loop end of a doubled cord E which is fastened

to a hook F fixed on the breech of the mortar.

According to this invention the gases generated by the propelling charge contained in a cartridge G, exert their thrust upon the stem C of the torpedo shell through the medium of a driving base piece II fitted with a gas check ring h of the usual type. Between the inner end of the driving base piece H and the rear end c² of the stem C there is arranged a shock absorber I of plastic material for instance lead. The driving base piece II on being driven forward by the explosion of the propelling charge, crushes the shock absorber which is thereby forced on one side into a recess c² provided in the end c², while on the other side it dovetails itself as it were into recesses h¹ (Fig. 3) formed in the end of the driving base piece H. The driving base piece fitted with the shock absorber I, is thereby converted into one piece, as it were, with the torpedo shell proper at the very commencement of the action of the propelling gases by becoming bodily engaged in the rear part of the neck C, to which it thus imparts its forward and rotating motions; the stem C being guided at its forward portion by the vaned sleeve D. The latter is taken along in the usual manner by a bolster provided on the stem C. In the example this bolster is constituted by a wedge-shaped ring J.

According to this invention a further shock absorber is provided on the stem C in front of the driving bolster J. In the example this shock absorber is constituted by a leaden ring K provided at its rear with a coiled cord L serving as an elastic buffer.

The shock absorber K—L is crushed or compressed between the vaned sleeve D and the driving bolster J, which latter becomes jammed at its conical front end into the flaring rear end d of the sleeve D. As soon as the vaned sleeve D is carried along it becomes, as it were, one piece with the stem C. From that moment a complete and rigid union is established between the torpedo shell (bomb B and guiding stem C), the driving base piece II and the steadyng vaned sleeve D.

Having now described my invention what I claim as new and desire to secure by Letters Patent is:—

1. In combination, a stem adapted to extend into a gun and a projectile or bomb supported on said stem outside of the gun, and means normally detached from said stem but supporting the same near the gun muzzle, said means becoming automatically attached to said stem when the gun is fired.

2. In combination, a stem adapted to extend into a gun and a projectile or bomb supported on said stem outside of the gun, and means provided with steadyng vanes normally detached from said stem but sup-

porting the same near the gun muzzle, said means becoming automatically attached to said stem when the gun is fired.

3. In combination, a bomb or projectile of larger caliber than the bore of the gun for projecting the same, a stem secured to said projectile and extending into the gun, and means normally detached from said stem but supporting the same near the gun muzzle, said means becoming automatically attached to said stem when the gun is fired.

4. In combination, a bomb or projectile of larger caliber than the bore of the gun for projecting the same, a stem secured to said projectile and extending into the gun, and means provided with steadyng vanes normally detached from said stem but supporting the same near the gun muzzle, said means becoming automatically attached to said stem when the gun is fired.

5. In combination, a bomb or projectile of larger caliber than the bore of the gun for projecting the same, a stem secured to said projectile and extending into the gun, a sleeve provided with vanes surrounding said stem near the gun muzzle and supporting said stem, and means automatically attaching said sleeve to said stem when the gun is fired.

6. In combination, a bomb or projectile of larger caliber than the bore of the gun for projecting the same, a stem secured to said projectile and extending into the gun, a sleeve provided with vanes surrounding said stem near the gun muzzle and supporting said stem, means automatically attaching said sleeve to said stem when the gun is fired, and means normally holding said sleeve against the muzzle of the gun.

7. In combination, a stem adapted to extend into a gun and a projectile or bomb supported on said stem outside of the gun, means normally detached from said stem but supporting the same near the gun muzzle, said means becoming automatically attached to said stem when the gun is fired, and a shock-absorber carried by said stem and engaging said means to prevent breakage of the same.

8. In combination, a stem adapted to extend into a gun and a projectile or bomb supported on said stem outside of the gun, means provided with steadyng vanes normally detached from said stem, said means becoming automatically attached to said stem when the gun is fired, and a shock-absorber carried by said stem and engaging said means to prevent breakage of said vanes.

9. In combination, a stem adapted to extend into a gun and a projectile or bomb supported on said stem outside of the gun, a vaned sleeve surrounding said stem near the muzzle of the gun, a wedge-shaped member secured to said stem and adapted

to be driven into said sleeve, and a shock-absorber arranged in front of said member.

10. In combination, a stem adapted to extend into a gun and a projectile or bomb supported on said stem outside of the gun, a vanned sleeve surrounding said stem near the muzzle of the gun, a wedge-shaped member secured to said stem and adapted to be driven into said sleeve, and a shock-absorber arranged in front of said member, said shock-absorber comprising a ring and an elastic element.

11. In combination, a stem adapted to extend into a gun and a projectile or bomb supported on said stem outside of the gun, means supporting said stem near the gun muzzle, and a base piece coöperating with said stem within the gun and being of the same caliber as the gun.

20. 12. In combination, a stem adapted to extend into a gun and a projectile or bomb supported on said stem outside of the gun, a base piece coöperating with said stem within the gun and being of the same caliber as the gun, and shock-absorbing means between said base piece and stem.

13. In combination, a stem adapted to extend into a gun and a projectile or bomb supported on said stem, a base piece having its movement influenced by the rifling of the gun, and means automatically connecting said base piece and stem.

14. In combination, a stem adapted to extend into a gun and a projectile or bomb supported on said stem outside of the gun, a base piece having its movement influenced by the rifling of the gun, shock-absorbing means arranged between said base piece and stem, and means whereby said shock-absorbing means automatically connects said base piece and stem when the gun is fired so that the movement of the base piece, stem and projectile is influenced by the gun rifling.

15. In combination, a stem adapted to extend into a gun and a projectile or bomb supported on said stem, a base piece having its movement influenced by the rifling of the gun, and a plastic body arranged between the base piece and stem and automatically connecting said parts when the gun is fired.

16. In combination, a stem adapted to extend into a gun and a projectile or bomb supported on said stem, a base piece having its movement influenced by the rifling of the gun, said stem and base piece being provided with recesses, and a plastic body arranged between said base piece and stem and being forced into said recesses when the gun is fired, whereby the movement of said stem is influenced by the gun rifling.

17. In a device of the character described, a cartridge for a gun, a base piece in juxtaposition to said cartridge, a stem coöperating with said base piece, and a bomb or projectile removably secured to the end of said stem outside of the gun.

18. In a device of the character described, a cartridge for a gun, a base piece in juxtaposition to said cartridge and provided with a gas-check ring, the movement of said base piece being controlled by the rifling of the gun, a stem having one end in juxtaposition to said base piece, means for automatically securing said stem and base piece together, and a bomb or projectile carried by the other end of said stem.

19. In a device of the character described, a cartridge for a gun, a base piece in juxtaposition to said cartridge, a stem coöperating with said base piece, a bomb or projectile removably secured to the end of said stem outside of the gun, and means supporting said stem near the gun muzzle, said means being automatically attached to said stem when the gun is fired.

20. In a device of the character described, a stem adapted to project into a gun provided with rifling, a bomb or projectile carried by said stem outside of said gun, and means whereby said stem and projectile are automatically made subject to the gun rifling when the gun is fired.

21. In a device of the character described, a bomb or projectile provided with a rearwardly-extending sleeve, a stem having one end adapted to extend into the muzzle of a gun and the other end into said sleeve, and means for readily attaching and detaching said bomb or projectile to and from said sleeve.

22. In combination, a stem adapted to extend into a gun and a projectile or bomb supported on said stem outside of the gun, means provided with steadyng vanes normally detached from said stem, said means becoming automatically attached to said stem when the gun is fired, a shock-absorber carried by said stem and engaging said means to prevent breakage of said vanes, a base piece coöperating with said stem within the gun and being of the same caliber as the gun, and shock-absorbing means between said base piece and stem.

In testimony whereof I have signed this specification in the presence of two subscribing witnesses.
